UNITED STATES PATENT OFFICE

2,159,089

DRILLING MACHINE SWITCH

Robert K. Jeffrey, Bexley, Ohio, assignor to The Jeffrey Manufacturing Company, a corporation of Ohio

Original applications May 14, 1934, and January 16, 1936, Serial Nos. 725,504 and 59,421. Divided and this application March 12, 1938, Serial No. 195,599

11 Claims. (Cl. 200—147)

The present invention relates to an improved switch particularly useful with portable drilling units of the manually supported type although it may have a general application.

5 One of the objects of the invention is the provision of an improved and compact but highly efficient circuit controlling switch for a motor, such as the motor of a drilling machine.

A further object of the invention is the provision of improved and efficient electric switch 10 mechanism for controlling an electric motor of a drilling machine, including a magnetic blow-out which acts to blow out arcs as the circuit is simultaneously broken in two places by a snap 15 action.

Other objects of the invention will appear hereinafter, the novel features and combinations being set forth in the appended claims.

In the accompanying drawings, 20 Fig. 1 is a wiring diagram showing the electrical connections from the source of power to the motor through the electric switch;

Fig. 2 is a sectional plan view of a portion of a drilling machine comprising the switch housing, switch and operating mechanism;

Fig. 3 is a sectional view of the control switch taken on the line 3—3 of Fig. 2 looking in the direction of the arrows;

30 Fig. 4 is a fragmentary sectional elevational view of the switch mechanism and the mechanism for effecting the operation thereof manually to closed position and automatically to open position;

35 Fig. 5 is a sectional view taken on the line 5—5 of Fig. 4, looking in the direction of the arrows, and showing the relative positions of the switch operating handle and the switch yoke when the switch is closed;

40 Fig. 6 is a view similar to Fig. 5, but showing the relative positions of the switch operating handle and switch yoke when the switch is in open position;

Fig. 7 is a sectional view of the switch taken 45 on the line 7—7 of Fig. 4, looking in the direction of the arrows;

Fig. 8 is a view similar to Fig. 7, but showing the switch in closed position, and

50 Fig. 9 is a sectional view somewhat similar to Fig. 4 but with certain parts broken away to show more clearly the elements of the switch.

This application comprises a division of my application for Drilling machines, Serial No. 725,504, filed May 14, 1934, and of my applica- 55

tion for a Drilling machine switch, Serial No. 59,421, filed January 16, 1936.

Referring more particularly to the drawings, it will be observed that the switch is illustrated as controlling a drilling machine parts of which 5 are shown in the drawings. Said electric controlling switch is very compactly arranged in a flame-proof casing C, as shown in Fig. 2.

Mounted in the tubular extension 48 of the casing or compartment C is a bushing 52 to serve 10 as a journal bearing for the cup shaped sleeve 49 which is secured by means of the pin 50 to the inner end portion of the hollow switch operating handle 47. The bushing 52 is secured to the tubular extension 48 by means of the pin 15 shown at 48a. A portion of the bushing 52 extends inwardly to form fixed abutments 52a and 52b as shown in Figs. 5 and 6, which abutments are stationary relative to the supporting casing or frame of the drilling machine. 20

The outer end of the sleeve 49 is provided with an annular flange 49a which is adapted to abut against the outer end of the bushing 52 as shown in Fig. 2. A retaining washer 119a and a snap ring 119 serve to hold the annular flange 25 49a in its position against the outer end of the bushing 52.

The outer end of the tubular support 48 is recessed not only to provide annular seats for the washer 119a and the snap ring 119 but also 30 the inner end of the coil spring 57 which inner end is secured to the tubular support 48. The outer end of the spring 57 is secured at 58 to the tubular handle 47 as shown in Figs. 2 and 4. The inner end 51 of the sleeve 49 is provided with an extension 49' which is provided 35 with a spring seat 51a (Figs. 5 and 6), and a movable abutment 51b. When the handle 47 is released the spring 57 acts to move the abutment carrier 49' to a position shown in Fig. 6. 40

Projecting axially from the center of the plate 51 as shown in Figs. 4, 5 and 6, is a bearing 54 about which is coiled the intermediate portion of the spring 60, one end of which at 60b rests against the seat 51a and the other end of which at 60a bears against the yoke 53 one end of which is journaled on the bearing 54 and the other end of which is provided with a shaft 54a which is journaled in the bearing 55 as shown in Fig. 4. The shaft 54a is in axial alignment 50 with the bearing 54. 45

The yoke 53 is connected to electric switch mechanism for controlling the starting and stopping of the electric motor by means of the circuits and connections diagrammatically illus- 55

trated in Fig. 1. When the handle 47 is turned in one direction the switch will be closed and the motor started to operate the drilling machine. The rotation of the handle 47 to close the switch places such tension in the spring 57 that when the handle 47 is released by the operator the spring 57 will act automatically to restore the switch to its open position and thereby effect stopping of the motor.

10 Inasmuch as it is desirable to open the switch with a snap action or effect very quick separation of the contacts of the electric switch in order to reduce the arcing to a minimum when the circuit of the electric motor is broken, compactly arranged automatic switch operating mechanism is mounted in the compartment C and connected to the handle 47 as shown in Figs. 2, 3, 4, 7, 8 and 9.

15 The switch mechanism is mounted between blocks of insulating material 77 and 93 (Fig. 3) which are secured to the bosses 96^a and 99 by means of the screw-threaded ends of the cap screws 96 and 98 and the insulating spacing tubes 97 and 66.

20 25 The spacers 66 may be integral with the insulating block 77 and each provided with a depending support 66' (Fig. 9) provided with aligned openings for receiving the inner ends of laterally projecting bearings 65, 65 which may be pinned to the support 66' as indicated at 65^a in Fig. 9.

30 35 As shown in Figs. 3, 7, 8 and 9, insulating blocks 61 are provided with upwardly opening slots or recesses 64 to fit over the bearings 65 from the underside of the latter. The insulating blocks 61 are rigidly connected by the transverse insulating cross-piece 61'. Between the blocks 61 and parallel to the crosspiece 61' is mounted a transverse pin 69 having a groove 70 intermediate its ends for receiving the lower end 70' of the spring 68, the upper end of which is hooked at 71 through the opening 72 at the upper central portion of the yoke 53.

40 45 Each of the insulating blocks 61 carries a metallic strip or finger 62 the lower end of which is pinned at 83 to the copper contact 63. At the upper end of each metal strip 62 is a square hole adapted to fit loosely over the squared head 78 of a screw inserted in the upper portion of the block 61 as shown in Figs. 7, 8 and 9. This arrangement prevents the contact carrying strips or fingers 62 from swiveling in its own plane but a limited movement of the strip 62 transversely of its own plane is permitted to secure 50 55 a wiping action of the contact 63 against the metal plate 73 when the switch is moved from its open position in Fig. 7 to its closed position in Fig. 8.

55 60 A pin 79 secured to each block 61 projects through a hole in the strip 62 intermediate its ends. Each pin 79 is provided with a collar 80 with a spring 81 between the same and the outer surface of the strip 62 as shown in Figs. 7 and 8. A cotter pin 82 holds the collar 80 in place. 65 70 When the block 61 is moved to the position shown in Fig. 8 the spring 81 holds the contact 63 yieldingly against the metal plate 73. As shown in Figs. 7 and 8, the metal plate 73 is secured by means of the cap screw 74 to the base block 76 of insulating material which may be integral with the insulating block 77.

75 By referring to Fig. 9, it will be seen that spaced-apart electric terminals may be afforded by the metal plates 75, 75 secured to the metal plates 73, 73 by means of the screws 75', 75.

Electric terminals 62^a, 62^a are riveted to the contact carrying strips 62 as shown at 62^b, 62^b. As shown in Fig. 1, the switch is two-pole in that one electric conductor extends through the contacts 63, 73 and another conductor extends through the contacts 63', 73', said conductors being respectively connected to the supply mains. 5

10 In order to minimize arcing during operation of the switch mechanism, there is mounted between the insulating blocks 77 and 93 within the space between the base blocks 76, 76, a blow-out coil 84 having a flux concentrating iron core 84^a the ends of which project through openings into insulating blocks 84^b, 84^b so as to occupy positions closely adjacent to the points of engagement between the contacts 63 and the plates 73. As shown in Fig. 1 the winding of the blow-out coil 84 is connected in the motor circuit and in series with the two sides of the double-pole switch. When the switch is open the blow-out coil acts to lengthen the arcs between the contact 63 and the plate 73 aiding the disruption of such arcs. 15 20

25 As a precaution against the burning of any of the parts when such arcs are formed upon the breaking of the circuits at the switch contacts in the compartment C, plates 135, 135 of asbestos or other non-inflammable material are secured at 145, 145 to the outer surfaces of the base blocks 76 at the sides of the switch mechanism 30 as shown in Fig. 4. The securing means at 145, 145 may be screws extending into the blocks 76 as shown in Figs. 7 and 8. The end blocks 84^b, 84^b of the blow-out coil are also preferably made of asbestos or other non-inflammable material to protect coil 84. 35

40 A safety fuse 91 is mounted between clips 92, 92 and connected in the motor circuit as shown in Fig. 1. The compartment C in which the switch mechanism is mounted is provided with a cover 105 screw-threaded to closed position and sealed in closed position as illustrated at 120 in Fig. 2. Access may be had to the interior of the compartment C for renewal of the blown-out fuse 91 by removing the cover 105 but not until 45 the seal 120 has been broken.

45 Secured to the insulating block 93 by means of the screws 101, 101 is a plate of insulating material provided with upper and lower extensions 102 and 103 at right angles to the block 93 and extending across the outer ends of the clips 92, 92 as shown in Fig. 3 so as to prevent any possibility of grounding of the clips 92, 92 through the heads of the screws 92, 92 to the metal frame or casing of the drilling machine. 50 55 A connector 104 as shown in Fig. 3 for the conductor 126 shown in Fig. 1 may be mounted back of a curved portion 143 of the shield 144 for protection thereby.

60 65 In order properly to space the ends of the iron core 84^a of the blow-out coil 84 from the switch contacts 63, 73 a retaining block 95 of insulating material is riveted at 94 to the inner surface of the insulating block 93 as shown in Fig. 3. The lower corners of the block 95 are 65 suitably notched to fit over the beveled upper edges 84^c of the rectangular end insulating blocks 84^b. The latter are also clamped by means of the screws 96 and 98 between the insulating blocks 93 and 77. 70

75 It should be particularly noted that when the cover 105 is removed the entire switch unit may be removed and taken apart for the purpose of repair or replacement. This is particularly true with respect to the contact carrying mechanism 75

because the open slots 64 permit the insulating block 61 together with the crosspiece 61' to be removed from the bearings 65, 65 against the action of the spring 68. If desired, the contact carrier may be readily detached from the hook 10' at the lower end of the spring 68. When the retaining ring 119 shown in Fig. 4 is removed the handle 47 may be removed from the journal bearing 52 thus disconnecting the handle from the yoke and permitting the removal of the latter from the bearing 55.

When all of the parts of the drilling machine are in assembled relation ready for operation, the electric switch may be closed to effect starting of the motor by rotation of the handle 47 against the action of the spring 57 in an anti-clockwise direction as viewed in Fig. 5. When the switch is open the yoke 53 occupies the position shown in Fig. 5 or the position shown in full lines in Fig. 2.

When the handle 47 is rotated in an anti-clockwise direction as viewed in Fig. 5 the abutment 51^b will engage the yoke 53 to swing the same from its full line position shown in Fig. 3 toward its dotted line position. In doing so, the outer central portion of the yoke 53 engages the free end of the spring clip 121 which is secured to the inner surface of the compartment C as shown in Fig. 3. However, the yoke 53 clears the spring clip 121 by the time that the spring 68 moves to a position to the left of the axis of the bearing 65 as viewed in Fig. 3 whereupon the spring 68 is free to act to effect closure of both of the sets of contacts designated 63, 73 and 63', 73' in Fig. 1. When the switch is closed the yoke 53 is held against the fixed abutment 52^a with the abutment 51^b held manually against the other side of the yoke 53 as shown in Fig. 5. Furthermore, when the switch is closed the spring 60 has one arm 60^b resting against the seat 51^a and the other arm 60^a engaging that side of the yoke 53 remote from the abutment 51^b.

When it is desired to open the switch the handle 47 is released whereupon the stored tension in the spring 57 will act automatically to move the carrier 49' in a clockwise direction as viewed in Fig. 5 thereby continuing to move the abutment 51^b away from the yoke 53. The yoke 53 moves through a small angle to a position in engagement with the spring clip 121 due to tension in spring 60. At such time the spring 60 does not have sufficient tension to move the yoke 53 past the clip 121. In other words, the clip 121 prevents continued movement of the yoke 53 until a predetermined amount of tension is stored in the spring 60. The purpose of the retarding action of the spring clip 121 is to hold the yoke 53 in such position that the spring 68 may be at the left of the axis of the bearings 65 so that the switch will be held positively closed until it is ready to open with a snap action. That is to say, in order to prevent initial movement of the handle 47 towards switch opening position from causing the contacts 63 and 63' from separating from the plates 73, 73' the spring clip 121 causes the spring 60 to hold the switch positively closed thereby preventing arcing which would occur when the contacts 63, 63' are moved only a short distance from the plates 73, 73'. As rotation of the handle 47 continues in a clockwise direction as viewed in Fig. 4, the abutment 51^b moves farther away from and the abutment 51^a moves closer to the yoke 53, but the latter being held by the spring clip 121 causes increasing tension to be stored in the spring 60 until such tension is sufficient to overcome the holding effect

of the spring clip 121. Then the spring 60 moves the yoke 53 from under the spring clip 121, whereupon the spring 68 moves to the right of the center of the bearing 65 as viewed in Fig. 3, whereupon the contacts 63, 63' would be suddenly and quickly withdrawn from the contact plates 73, 73'. When the switch is in open position the yoke 53 will rest against the abutment 52^b as shown in Fig. 6 and the crosspiece 61' of the switch contact carrier will abut against the back of the insulating block 95 as shown in Fig. 3.

Fig. 1 shows diagrammatically the circuits and connections for the electric drill motor and the switch for controlling the same. The terminal hook 128 may be connected to a trolley wire in a mine to serve as the connector to the positive supply main 127 which is connected to the plate 73'. The hook 122 may be attached to the rail 131 of the mine track to serve as the connector to the negative supply main 123 which is connected to the contact plate 73. The motor is preferably compound wound so that it will not race under substantially no load and yet be capable of withstanding heavy overloads without overheating.

When the switch is closed the motor circuit may be traced in Fig. 1 to the conductor 127 through contacts 73', 63', fuse 91, conductor 126, series motor winding 85, motor armature 14, conductor 125, blow-out coil 84, contacts 63, 73 and thence to the negative conductor 123. The shunt field coil 85' is also energized as it is shunted across series winding 85 and armature 14.

In order to protect the operator of the drilling machine the casing or frame thereof is grounded by a conductor 130 connected at its outer free end to the rail 131 and at its inner end to the frame or casing of the machine as illustrated diagrammatically at 129 in Fig. 9. This grounding connection may be effected by connecting the conductor 130 to the head of a screw in metallic contact with the metal frame of the machine.

It is thus to be seen that I have provided a very efficient, light weight switch which will insure the opening of a circuit even under heavy load. It is well adapted for use in a hand operated coal drill, as above described, but it is not limited to this use.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In an electric drill switch, the combination with a base of insulating material, of a pair of spaced-apart fixed switch contacts carried by said base, a pivoted insulating carrier, spaced-apart movable switch contacts mounted on said carrier in co-operative relation to said fixed contacts to form two circuit breakers which close and open together, means for operating the switch including the separation of the movable contacts from the fixed contacts with a snap action, a common blow-out coil connected in series with both circuit breakers and having poles at its opposite ends, and means for mounting said blow-out coil on said base with said poles closely adjacent the points of engagement between the movable contacts and the fixed contacts of said circuit breakers to aid the said snap action in extinguish-

ing the arcs between the disengaging contacts when the switch is opened.

2. In an electric drill switch, the combination with a base of insulating material, of a pair of spaced-apart fixed switch contacts mounted thereon, a carrier of insulating material pivotally mounted on said base, movable switch contacts carried by said pivoted carrier in cooperative relation to said fixed contacts to form two circuit breakers which close and open together, a common blow-out coil connected in series with both circuit breakers and having end poles, means for mounting said blow-out coil on said base between said fixed contacts with its end poles closely adjacent thereto, and non-inflammable plates mounted adjacent said fixed contacts at the outer sides thereof with such fixed contacts intervening between such plates and the end poles of the blow-out coil, and means for actuating said pivoted carrier to effect engagement or disengagement of the fixed and movable contacts.

3. In an electric drill switch, the combination with two pair of aligned circuit making and breaking contacts, of mechanism constructed and arranged to open said contacts together, and a magnetic blow-out coil connected in circuit with both of said pair of contacts and positioned to blow out arcs formed by them when opened.

4. In an electric drill switch, the combination with a pair of stationary contacts, a pair of movable contacts associated therewith, a common blow-out coil between cooperating pairs of said contacts and connected in series with each pair and adapted to blow out arcs formed thereby, and heat resisting plates of insulating material positioned laterally of said contacts.

5. In an electric drill switch, the combination with a base plate, of a pair of spaced stationary contacts mounted thereon, cooperating movable contacts therefor, means constructed and arranged to snap said cooperating contacts open, and a blow-out coil positioned between cooperating pairs of contacts and connected in series therewith to blow out arcs from each simultaneously when said contacts are opened.

6. In an electric drill switch, the combination with two pairs of separable contacts, of a common magnetic blow-out coil positioned between and with its ends adjacent to said contacts and connected in series therewith whereby it is adapted to blow out arcs generated when said pairs of contacts separate.

7. In an electric drill switch, the combination with two pairs of contacts, of means to separate said contacts with a snap action, and a single

magnetic blow-out coil connected in series with said contacts having a flux concentrating core and positioned to blow out arcs formed by separation of said contacts.

8. In an electric drill switch, the combination with a base of insulating material, side protecting plates mounted on said base, a centrally disposed blow-out coil mounted on said base with its ends extending toward and spaced from said plates, and a pair of separable contacts between each end of said coil and a side plate and connected in series with said coil.

9. In an electric drill switch, the combination with a base of insulating material, of a pair of spaced stationary contacts carried thereby, a block pivotally mounted on said base, spaced movable contacts carried by said block one cooperating with each stationary contact, a plate positioned from said base, means supporting said plate in spaced relation to said base, a magnetic blow-out coil mounted between said base and plate and positioned and connected to extinguish arcs from both pairs of cooperating contacts, and snap action mechanism for operating said pivoted block.

10. In an electric drill switch, the combination with a base of insulating material, of a pair of spaced stationary contacts carried thereby, a block pivotally mounted on said base, spaced movable contacts carried by said block one cooperating with each stationary contact, a plate positioned from said base, means supporting said plate in spaced relation to said base, a magnetic blow-out coil mounted between said base and plate and positioned and connected to extinguish arcs from both pairs of cooperating contacts, and means carried by said plate for limiting movement of said pivoted block in one direction.

11. In an electric drill switch, the combination with a base of insulating material, of a pair of spaced stationary contacts carried thereby, a block pivotally mounted on said base, spaced movable contacts carried by said block one cooperating with each stationary contact, a plate positioned from said base, means supporting said plate in spaced relation to said base, a magnetic blow-out coil mounted between said base and plate and positioned and connected to extinguish arcs from both pairs of cooperating contacts, snap action mechanism for operating said pivoted block, and a stop carried by said plate for limiting movement of said pivoted block in the circuit opening direction.
